MAX SPIRO, OF SEA GATE, NEW YORK.

WATCHCASE.

Application filed May 9, 1925. Serial No. 28,996.

The main object of this invention is to provide an ornamental and efficient wrist watch having several novel characteristics. The wrist watch is composed of a movement 5 which is retained in a carrier, the carrier being removably mounted in a casing. The invention concerns itself with the movement carrier and casing, and means for retaining a dial in position over the movement carrier so that no shifting of the dial is possible when the watch is shaken. The outer casing of the watch is composed of a pair of members which are releasably locked to each other and when open or dislocated 10 from each other, expose either the bottom of the movement or the dial. The casing has means thereon which cooperates with additional means on the movement carrier for retaining said movement carrier in place 15 20 in one unit of the casing when the casing has been dislocated or spread apart.

The above and other objects will become apparent in the description below, in which characters of reference refer to like-named 25 parts in the drawing.

Referring briefly to the drawing, Figure 1 is a front elevational view of the watch as worn.

Figure 2 is a sectional elevational view 30 taken longitudinally thru the center of one type of watch in which the movement carrier is retained in the upper half of the outer casing.

Figure 3 is a view similar to Figure 2, 35 showing the modified type of device in which the movement carrier is retained in the lower half of the outer casing.

Figure 4 is a perspective view of the dial used in the watch.

Figure 5 is a perspective view, showing 40 the lower half of the casing unit of the modified type of catch with a portion of the movement carrier mounted in place therein.

Figure 6 is a perspective view of the 45 movement carrier per se.

Referring in detail to the drawing, the numeral 10 indicates the upper half of the preferred type of watch casing. This casing is formed hollow of a unit of material 50 and provides a shell substantially square in outline which has arms 11 extending therefrom from the corners mutually parallel to each other. These hollow arms in the preferred type of device have openings 12 therein on the mutually adjacent

walls and into these holes, the ends of telescopic push pins 13 are inserted. The face 14 of the rectangular portion of the casing serves as a frame for the watch crystal which is fitted into place in the frame and 60 is ornamented around its rim, as illustrated, or in any other fashion desired. The casing which completely encloses the watch is comprised of two members, an upper unit described as member 10, and a lower unit 15 65 which is of the same outline as the casing unit 10, but has no opening, as is the case with the upper frame 10. This casing unit is also provided with arms 16 which align with the arms 11 of the upper frame and 70 form a compact casing in the chamber of which the watch movement is mounted. The side walls 17 of the upper frame unit 10 between the arms 11 thereof have semi-circularly curved tongues 18 extending 75 thruout the greater portion of the length thereof. These tongues are adapted to co-operate with converging side walls 19 formed between the arms 16 of the lower casing 15, when the casing members 10 and 80 15 are mutually interlocked. In the modified type of watch casing illustrated in Figure 3, the tongues 20 form projections which extend upwardly from the walls 19 of the casing 15 and are adapted to engage converging walls 21 of the upper casing member 10, that is, the relation of the tongue to its opposite member is directly reversed 85 in the modified type of casing. These tongues, as previously stated, are bent semi-circularly and project inwardly in the compartment formed by the interlocked casing frame 10 and 15. The semi-circular portions of these tongues serve additionally as 90 a means for locking the movement carrier 95 in place in the frame of which the tongues form a part. In the modified type of casing, the tongues form a part of the lower casing frame 15, consequently, the movement carrier is releasably fixed by the tongues 100 within this lower casing frame 15, and in the preferred form, the reverse is true. The movement carrier comprises a flat plate 22 having side walls 23 and end walls 24. The end walls 24 are provided with deformed 105 portions which present channels 25 in which the semi-circular portions of the tongues 20 of the cooperating casing frame 15 or 10 is adapted to be received in securing the 110 movement carrier in the particular casing

frame. This member forming the movement carrier is adapted to house the entire watch movement therein and the plate 22 is provided with the relatively large opening 26 thru which access may be had to the face portion of the movement. Near each one of the corners of the movement carrier plate 22, ears 27 are provided by slitting the material forming the plate 22 on three sides 10 of a rectangle and bending the enclosed portion angularly upward, as indicated in Figures 5 and 6. These ears serve as a position member for a dial plate 28 which has its face provided with the usual watch numbers 29, and at its corners, has cut-out portions 30 which are adapted to receive the ear portions 27 of the movement carrier when the dial plate is laid upon the face of the plate 22. An additional member, detachable from the movement carrier, is adapted to cooperate therewith in retaining the movement in place in the carrier. This additional member comprises a rectangular plate 31 which is of the same size as the plate 22 and is also provided with an opening 32 which exposes the greater portion of the contained movement in the movement carrier so that the same may be repaired or observed, as desired. This retainer plate 31 has at each of its corners, an extension which forms an integral part of the plate 31 and are bent at right angles thereto to provide flexible legs which are inserted into the carrier frame and lie in contact with the walls 24.

The main features of this watch case are that a watch movement may be mounted in a movement carrier, the movement carrier mounted within an outer casing consisting 40 of two units which interlock without the aid of any tools, or as is commonly used, solder. The watch movement is mounted within the movement carrier which serves as a housing for the movement and then the plate 22 of the movement carrier is covered by the dial plate 28 which is positioned by inserting the angularly up-turned ears 27 into the cut-out portions 30 formed on the dial plate. By having these ears 27 on the movement carrier cooperate with the cut-out portions 30

on the dial plate, shifting of the dial plate is, as is so common, eliminated. In the preferred type of device, the movement carrier is mounted in the upper unit 10 of the casing, as this unit is provided with semi-circularly curved tongues 18. The curved portions of the tongues are adapted to enter into the channels 25 provided by deforming the walls 24 of the movement carrier and in this manner, the entire movement carrier is held in retained position within its particular casing unit 10. In Figure 3, the modified type of watch casing is shown whose point of dissimilarity from the preferred form is that the tongues 20 form a part of the lower casing unit 15 and serve to expose the upper half of the movement carrier, as illustrated in Figure 5. After the movement carrier has been secured in place in either the casing unit 10, as in the preferred type of watch, or as in the modified type of watch, in the lower casing unit 15, the tongues 21 are adapted to cooperate by engaging the opposite casing unit to lock the units 10 and 15 to each other, as indicated in Figures 2 and 3. Thus a complete watch casing, including the outer casing, a movement carrier, and a dial, is being shown as completely assembled without the aid of any tools, as is the purpose of the invention.

I claim:—

In a watch having a casing consisting of two interlocking members, one of said members having oppositely disposed inwardly curved tongues, a movement carrier engaging the casing having said tongues comprising a flat plate square in outline, side walls on all four sides of said plate, flat-bottomed recesses formed in the walls of two opposing sides, said tongues registering in said recesses to retain the movement carrier in place in one of the casing members, said recesses being depressed inwardly and toward each other forming channels open on the outer surfaces of the walls, said movement carrier being open on one side, the casing members when interlocked engaging and releasably retaining the movement carrier in position.

In testimony whereof I affix my signature.
MAX SPIRO.
